UNITED STATES PATENT OFFICE.

THOMAS A. NAYLOR, OF BALTIMORE, MARYLAND.

CONVEYER FOR COAL-CARTS.

SPECIFICATION forming part of Letters Patent No. 314,869, dated March 31, 1885.

Application filed January 19, 1885. (No model.)

To all whom it may concern:

Be it known that I, THOMAS A. NAYLOR, of Baltimore city, State of Maryland, have invented certain new and useful Improvements 5 in Conveyers for Coal-Carts, of which the following is a specification, reference being had to the accompanying drawings, forming part hereof, in which—

Figure 1 is a top plan view with the body of 10 the cart removed. Fig. 2 is a rear end view, and Fig. 3 is a side elevation, of the conveyer. Fig. 4 is a side elevation of my device with the body of the cart thereon, and Fig. 5 is an end view of Fig. 4.

Like letters of reference mark similar parts 15 in all figures.

My invention relates to an improved coal-conveyer for carts, dumping-wagons, &c.

The object of my improvement is to facilitate 20 the placing of coal into cellars, and to overcome the difficulties heretofore experienced in elevating the body of the cart with the full load of coal therein, my invention obviating entirely the raising of the cart; and it 25 consists in the peculiar construction, arrangement, and combination of parts, as will be hereinafter explained.

Referring to the drawings by letter, A is the frame; A', a stationary rod running from 30 front to rear. A² is a square rod, also running parallel with rod A', both being journaled in the front and rear ends of the cart. Rod A² has near its rear end and on the inside of the frame A a gear-wheel, B, rigidly 35 affixed thereto, gearing into still another gear-wheel, B', on the end of a shaft, B², which extends through two supports, b b, the said shaft extending through the side of frame A, upon the end of which is a crank, b'.

C is a cross-beam through which rods A' A² pass, the square rod A² revolving in its respective ends of said cross-beam C by means of a spool (not shown) revolving in cylindrical holes cut therein, the said spools having 45 a square hole cut therein to admit of the square rod A² resting firmly therein.

C' is a gear-wheel with a square hole in its center, through which the square rod A² passes, and by which the said gear-wheel C' 50 is revolved.

C² is still another gear-wheel, gearing into gear-wheel C', from which it receives its mo-

mentum. This gear-wheel C² has also a square hole in its center through which passes the square end of rod C³, from which it receives 55 its rotating power. The outer end of rod C³ is loosely journaled in the outside of slot c, cut in the cross-beam C, while the other portion passes loosely through a hole cut in the inside of cross-beam C as well as a hole in the brace c'. Rod C³ has at its inner end a semicircular opening into which loosely fits the head of another rod, D, rigidly pinned therein by any well-known means, preferably the one shown. 60

Around rod D is rigidly affixed a worm-screw, D', which rests in a semicircular bed-plate, D². On the outer end of rod D is affixed an extension, d, for purposes hereinafter explained. The semicircular bed-plate D² is 70 rigidly affixed to the under side of cross-beam C at one end, while the outer end passes through proper slides affixed rigidly to the under side of the frame A at its rear end; or it may be arranged by resting in a skeleton 75 frame, E, as seen in Fig. 2, or in any well-known manner, without departing from the spirit of my invention.

The operation of my device may be described as follows: The cart-body having a central 80 sliding board or any other well-known means to let the coal fall through its center into the conveyer, and being placed upon the frame A, and it being desired to unload the coal, the conveyer is slid along upon rods A' A² until 85 it reaches the cellar-door. The opening in the cart-floor above referred to is then opened, when the coal will of itself fall through into the conveyer D², lying underneath thereof, when the crank b' is revolved by the operator, 90 which causes the gear-wheels B B' to revolve, thereby revolving the square rod A², which in turn revolves gear-wheel C', which also revolves gear-wheel C², which revolves the rod C³, thereby causing the rod D with its worm-screw D' to revolve rapidly, so that the coal, falling into the conveyer D², is ejected from the conveyer with such great velocity that the time occupied in unloading the cart is not to be at all compared with the time consumed in 95 hoisting the body of carts whose bodies have to be first raised and the coal then dumped into the chute.

When it is desired to reach a cellar at a dis-

tance too far remote from the conveyer herein shown, which is of itself a length of about seven feet, another section of the conveyer can be readily attached to the bearing *d*.

5 I am aware that conveyers for conveying grain have been heretofore used, and I do not claim such; but

What I do claim is—

1. The conveyer, in combination with a cart 10 or wagon, as herein shown and described, substantially in the manner as and for the purpose set forth.

2. In combination with a cart or wagon body, the worm-screw working within the trough by means of the universal joint, the 15 whole attached to the under side thereof, as herein shown and described, substantially in the manner as and for the purposes set forth.

THOS. A. NAYLOR.
